METAL-WORKING MACHINE

Homer G. Kellogg, Highland Park, Mich., assignor to Motor Products Corporation, Detroit, Mich., a corporation of New York

Application July 23, 1945, Serial No. 606,561

12 Claims. (Cl. 164—19)

1
This invention relates generally to work handling equipment and refers more particularly to apparatus for producing rivets.

In general, the present invention has as one of its objects to provide apparatus for making rivets at a rapid rate from a strip of preformed stock by a stamping operation. More particularly, it is an object of this invention to periodically feed a substantially continuous length of sheet metal stock through rivet forming equipment having means for simultaneously stamping a plurality of rivets from the stock during the intervals of rest of the latter.

A further object of this invention is to provide apparatus of the above type having rivet forming equipment comprising a punch movable in a direction toward a cooperating die assembly to punch rivets from the stock and having means responsive to movement of the punch unit for advancing the rivets to a retainer which is removably attached to the apparatus to enable the same to be readily detached when filled with the proper number of rivets. In apparatus equipped with a die assembly having a plurality of dies and with a punch unit having a corresponding number of punches, a separate retainer is associated with each punch to receive the rivets formed by the latter. When these retainers are filled with rivets, they may be simultaneously removed and assembled with suitable riveting machines for supplying rivets to the latter.

The foregoing as well as other objects will be made more apparent as this description proceeds, especially when considered in connection with the accompanying drawings, wherein:

Figure 1 is a semi-diagrammatic side elevation of a press having rivet forming means associated therewith;

Figure 2 is a fragmentary elevation, partly in section, of the rivet forming and conveying mechanism;

Figure 3 is an elevation partly in section showing the rivet retainer and the manner in which the latter is removably attached to the apparatus;

Figure 4 is a vertical sectional view through the punch unit and die assembly showing the punch unit in its raised position;

Figure 5 is a vertical sectional view taken substantially on the plane indicated by the line 5—5 of Figure 4;

Figure 6 is a view similar to Figure 5 showing a plurality of cooperating punch and die members;

Figure 7 is a cross sectional view taken sub-

stantially on the plane indicated by the line 7—7 of Figure 6;

Figure 8 is a perspective view of one of the rivets; and

Figure 9 is a cross sectional view taken on the plane indicated by the line 9—9 of Figure 4.

In general, the reference character 10 indicates a strip of sheet metal stock of substantial length which has previously been rolled to a T-shaped cross section indicated in Figure 4 of the drawings. The strip of stock 10 is fed step by step through a die assembly 11 and during the intervals of rest of the strip is punched by a punch unit 12 to form the rivets 13. During successive punching operations, the rivets 13 are advanced in superposed relation upwardly through the punch unit and are ultimately ejected through the top of the latter. As the rivets are ejected from the punch unit, they are introduced to tracks 14 and are guided by the latter into retainers 15. The retainers 15 are readily detachably connected to the delivery ends of the tracks 14 so as to enable the same to be removed when filled with rivets and assembled with suitable automatic riveting machinery for supplying the rivets thereto.

The apparatus briefly described above is adapted to be used in connection with a press 16 having a table 17 and having a platen 18 movable toward and away from the table 17. The die assembly 11 is supported in any suitable manner on the table 17 and comprises a plurality of rivet forming dies 19 secured in juxtaposition to each other by means of a pair of clamping plates 20.

The front plate 20 is formed with a longitudinally extending key 21, which engages in grooves 22 formed in the corresponding sides of the dies 19 and serves to hold the dies in proper relation to one another. Each die is formed with a cavity 23 corresponding in cross section to the cross sectional contour of the strip of stock or rivet 13 and the cavities in adjacent dies are in exact alignment with one another. The number of dies in the assembly 11 may, of course, vary in dependence upon the number of rivets to be produced simultaneously. For the purpose of illustration, the die assembly 11 comprises nine individual dies 19 with the result that nine rivets may be formed simultaneously from the strip of stock.

The punch unit 12 comprises nine individual punches 24 held in assembled relation by means of the clamping plates 25 respectively positioned on opposite sides of the punches 24. Each plate 25 is provided with a longitudinally extending key 26 for engagement in grooves 27 formed in the ad-

acent sides of the punches for holding the latter in proper position with respect to each other. The punch unit 12 is secured to the platen with the individual punches 24 in vertical alignment with respective dies 19.

As shown particularly in Figure 7 of the drawings, each punch 24 comprises a pair of laterally spaced plates 29 held in proper spaced relation to each other by means of spacers 30. The spacing between adjacent plates is predetermined to form vertical passages 31 respectively aligned with the cavities 23 in the dies 19 to receive the rivets 13. Suitable longitudinally extending projections 32 are formed on opposite sides of each plate 29 to provide ribs in the passages 31. The ribs or projections 32 function during the operative strokes of the punches to respectively form recesses 33 in opposite edges of the head portions on the rivets 13 and cooperate with the recesses subsequent to the punching operations to guide the rivets in an upward direction through the passage 31.

The spacers 30 are positioned between the plates 29 at the upper ends of the latter and the lower ends of the plates of each punch are adapted to straddle the aligned die member 19. Suitable projections 34 are formed on opposite sides of each plate 29 at opposite longitudinal edges of the latter and these projections slidably engage in recesses 35 formed in opposite sides of the die members 19. The construction is such as to provide for guiding the punches 24 during vertical movement of the latter by the platen 18.

The bottom edge of each plate 29 between the projections 34 is formed with a recess 36 and the bottom edge of the recess is fashioned with a depending projection 37 aligned with the ribs 32 at opposite sides of the punch plates. The recesses 36 in the punch plates receive the stock 10 at opposite sides of the die cavities 23 upon movement of the punches 24 downwardly relative to the dies and the edges of the recesses serve to sever the stock at opposite sides of the dies 19 to provide rivets 13 in the die cavities 23. The projections 37 cooperate with the ribs 32 to form the recesses 33 in opposite sides of the head portions of the rivets and these recesses 33 subsequently engage the ribs 32 on the punch plates 29 to guide the rivets 13. The lateral distance between adjacent punch plates, or in other words, the width of the passages 31 is such that the rivets are frictionally engaged by the plates, so that when the punch unit 12 is retracted from the die assembly, the rivets are retained between the punch plates. The scrap resulting from the punching operation drops out of the dies through the recesses 35.

It follows from the above that during successive punching operations, the rivets are moved upwardly in the punch passages 31 and assume the superposed relationship shown in Figure 4 of the drawings. In this figure of the drawings, the uppermost rivet 13 is illustrated as being ejected from the upper end of the punch into the track 14. It will, of course, be understood that a track 14 is provided for each punch and, accordingly, nine tracks are shown in the drawings. Upon reference to Figure 9 of the drawings, it will be noted that the tracks are channel-shaped in cross section and that the free edges of the side flanges are bent, rolled or otherwise formed to extend inwardly. The inwardly extending portions are indicated in the drawings by the reference character 40 and the portions 40 of each track respectively engage in the recesses 33 formed in opposite sides of the rivets.

As shown in Figures 1 and 2 of the drawings, the tracks 14 are secured to the platen 18 of the press 16 for movement as a unit with the platen and the receiving ends of the tracks are positioned

5 to receive rivets as the latter are ejected from the upper ends of the passages 31 in the punches 24. Five of the tracks 14 are curved to the left and the remaining four of the tracks are curved to the right, as viewed in Figures 1 and 2. It will, 10 of course, be understood that during successive punching operations, the rivets 13 are not only advanced upwardly through the punch passages 31 but are also moved along the tracks 14.

As the rivets are discharged from the ends of 15 the tracks 14, they are received by the retainers 15. Each retainer 15 comprises a length of track 41 similar in construction to the tracks 14 and having sockets 42 welded or otherwise suitably secured to opposite sides thereof. The sockets 20 42 respectively slidably receive pins 43 secured to opposite sides of the delivery end portion of each track 14. The number of rivet retainers 15 corresponds to the number of tracks 14 and when the sockets 42 are in assembled relation 25 with the pins 43, the tracks 41 on the retainers are respectively aligned with the delivery ends of the tracks 14. The arrangement is such that the rivets 13 ejected from the tracks 14 are received by tracks 41 on the retainers. The retainers 15 remain in assembled relationship with the tracks until they are filled with rivets, whereupon the filled retainers are replaced with empty retainers. The filled retainers may then be readily transported to an automatic riveting machine 30 for supplying rivets to the latter.

What I claim as my invention is:

1. In apparatus of the class described, a die having a cavity for receiving a strip of stock, means coacting with the die to punch parts from the stock including a punch having a passage 40 for receiving the parts and having means for slidably supporting the parts in superposed relation in the passage whereby preceding parts are advanced along the passage by succeeding parts 45 during the punching operation, and means for collecting the parts ejected from the punch passage.

2. In apparatus of the class described, a die having a cavity for receiving a strip of stock, a punch successively movable toward and away 50 from the die to punch parts from the stock, a vertical passage through the punch for receiving the parts, and means for slidably supporting the parts in superposed position in the passage 55 whereby preceding parts are advanced through the passage by succeeding parts in response to movement of the punch toward the die.

3. In apparatus of the class described, a die having a cavity for receiving a strip of stock, a punch successively movable toward and away 60 from the die to punch rivets from the stock, a vertical passage through the punch for receiving the rivets, means for slidably supporting the rivets in superposed position in the passage 65 whereby preceding rivets are advanced through the passage by succeeding rivets in response to movement of the punch toward the die, a removable retainer for the rivets, and means for directing the rivets ejected from the passage to the retainer.

4. In apparatus of the class described, a die having a cavity for receiving a strip of stock, a punch successively movable toward and away 70 from the die to punch rivets from the stock, a vertical passage through the punch for receiving 75

the rivets, means for slidably supporting the rivets in superposed position in the passage whereby preceding rivets are advanced through the passage by succeeding rivets in response to movement of the punch toward the die, a track for receiving the rivets ejected from the delivery end of the passage, and a retainer having a length of track registering with the delivery end of the first track and removable from the latter.

5. In apparatus of the class described, a die having a cavity for receiving a strip of stock, means coacting with the die to punch rivets from the stock including a punch having means for forming grooves in opposite sides of the rivets and having a vertical passage therethrough for receiving the rivets as the latter are punched from the stock, and vertical ribs projecting inwardly from opposite sides of the passage and engageable with the grooves in opposite sides of the rivets to guide the latter in superposed relation through the passage.

6. In apparatus of the class described, a die having a cavity for receiving a strip of stock, means coacting with the die to punch rivets from the stock including a punch having means for forming grooves in opposite sides of the rivets and having a vertical passage therethrough for receiving the rivets as the latter are punched from the stock, means for slidably supporting the rivets in superposed relation in the passage whereby preceding rivets are advanced through the passage by succeeding rivets during the punching operation, said rivet supporting means comprising vertical ribs projecting inwardly from opposite sides of the passage and engageable in the grooves in opposite sides of the rivets, and a track for receiving the rivets ejected from the passage and having opposed inwardly extending flanges for engagement in the grooves at opposite sides of the rivets.

7. In apparatus of the class described, a die having a cavity for receiving a strip of stock, a punch successively movable toward and away from the die to punch rivets from the stock with grooves in opposite sides thereof, a vertical passage through the punch for receiving the rivets, means for slidably supporting the rivets in superposed position in the passage whereby preceding rivets are advanced through the passage by succeeding rivets in response to movement of the punch toward said die, said last named means comprising ribs extending inwardly from opposite walls of the passage and engageable in the grooves at opposite sides of the rivets, a track positioned to receive the rivets ejected from the passage and having opposed inwardly extending flanges respectively engageable in the grooves at opposite sides of the rivets, and a removable retainer for collecting the rivets discharged from said track.

8. In apparatus of the class described, a die having a cavity for receiving a strip of stock, a punch successively movable toward and away from the die to punch rivets from the stock, a vertical passage through the punch for receiving the rivets, a track having the entrant end registering with the upper end of the passage, and means for slidably supporting the rivets in superposed position in the passage whereby preceding rivets are advanced through the passage and along said track by succeeding rivets in response to movement of the punch toward said die.

9. In apparatus of the class described, a die having a cavity for receiving a strip of stock, a punch successively movable toward and away from the die to punch rivets from the stock, a vertical passage through the punch for receiving the rivets, a track movable with the punch and having the entrant end registering with the upper end of the passage, a retainer removably connected to the delivery end of the track for receiving rivets discharged from the latter, and means for slidably supporting the rivets in superposed position in the passage whereby preceding rivets are advanced through the passage, along the track and into engagement with the retainer by succeeding rivets during each punching operation.

10. In apparatus of the class described, a die unit comprising a plurality of dies supported in juxtaposition and adapted to receive a strip of stock, a corresponding number of punches movable in directions toward and away from the dies to simultaneously punch a plurality of rivets from the stock, a vertical passage through each punch for receiving the rivets formed by the latter, and means for slidably supporting the rivets in superposed position in said passages whereby preceding rivets are advanced along the passages by the succeeding rivets during each punching operation.

11. In apparatus of the class described, a die unit comprising a plurality of dies supported in juxtaposition and adapted to receive a strip of stock, a corresponding number of punches movable in directions toward and away from the dies to simultaneously punch a plurality of rivets from the stock, a vertical passage through each punch for receiving the rivets formed by the latter, a track leading from the delivery end of each passage and movable as a unit with the punches, a rivet retainer removably attached to the delivery end of each track, and means for slidably supporting the rivets in superposed position in the passages whereby preceding rivets in the passages are advanced by the succeeding rivets through the passages, along the tracks and into engagement with the retainers.

12. In apparatus of the class described, a die having a cavity through which an elongated length of stock is fed, a punch successively movable toward and away from the die in timed relation to the movement of the stock to punch parts from the stock, means for cooling the parts as they are formed and for supporting the parts in a stack whereby preceding parts are advanced by succeeding parts during each punching operation, and a removable retainer positioned to receive the parts and having means for slidably supporting said parts in juxtaposition to each other lengthwise of the retainer.
